IGNITION APPARATUS FOR INTERNAL COMBUSTION ENGINES

Frank Raymond Faber Ramsay, London, England,
assignor to D. Napier & Son Limited, London,
England, a company of Great Britain

Application March 30, 1940, Serial No. 326,992
In Great Britain April 13, 1939

9 Claims. (Cl. 123—148)

This invention relates to energising apparatus for supplying low tension current impulses to the primary winding of a high tension magneto of an internal combustion engine to facilitate starting.

For this purpose it has been proposed to provide a primary circuit comprising a battery and an interrupter of the buzzer type with switches for closing the primary circuit and connecting it to the primary winding of the magneto during starting. It is convenient to construct the energising apparatus and the switches controlling it as a unit and in prior proposals this has meant in practice that this apparatus must be arranged near the pilot or other person responsible for the control of the engine. This is, however, not always either convenient or desirable and the object of the present invention is to provide an improved arrangement which may be applied to the previously proposed apparatus referred to above, or to other apparatus of the kind referred to, for example the apparatus forming the subject of the present applicants' copending United States of America Patent application Serial No. 269,256, which will enable the energising apparatus to be disposed at a distance from the point of control, for example near the engine or magneto.

To this end in energising apparatus of the kind referred to for supplying low tension current impulses to the primary winding of a high tension magneto of an internal combustion engine according to the present invention, there is combined with a primary circuit including an interrupter and adapted to be connected to a source of current, an electromagnetically operated switch which controls the connection between the energising apparatus and the primary winding of the magneto and is adapted to close automatically when the primary circuit is energised and to open automatically when this circuit is deenergised.

Thus, a switch for closing the primary circuit may be provided adjacent to the point of control, while the energising apparatus itself, including the switch for connecting it to and disconnecting it from the primary winding of the magneto, may be disposed at any desired point.

Where, as will generally be the case, an interrupter of the buzzer type is employed, the electromagnetically operated switch may be actuated by the stray field from the coil of the buzzer. Thus, for example, the interrupting contacts of the buzzer may lie at one end of the core of the coil while the electromagnetically operated switch

lies at the other end thereof. In this case the coil conveniently has an open-ended core with a strip of metal constituting a magnetic link extending between but separated by gaps from the ends of the core for the purpose of concentrating the stray field.

In any case, the movable contact of the electromagnetically operated switch is conveniently of such weight that when the coil is energised it will 10 maintain the electromagnetically operated switch permanently closed in spite of the interrupted nature of the current flowing through the primary circuit. For example, the electromagnetically operated switch may comprise a comparatively heavy armature mounted upon a metal leaf which carries, preferably resiliently, two contacts insulated from one another and adapted to engage two fixed contacts, when the coil is energised so as to connect the energising apparatus to the 15 primary windings of two magnetos.

In such a case the armature is preferably connected to the metal leaf in such a manner that it can rock relatively to the leaf to a sufficient extent to enable the armature to bed properly upon 20 the end of the core of the coil without materially distorting the leaf. Thus the armature may be connected to the leaf at a single point, in which case the armature can rock relatively to the leaf in all directions without materially distorting it 25 or may be connected to the leaf so that it can rock relatively thereto only in one direction, e. g. about a line at right angles to the length of the leaf. In this way, buzzing of the armature due to its not bedding down properly on the core with 30 the result that the armature tends to rock about the point at which it engages the core and thus to distort the leaf, tends to be prevented.

The invention may be applied to apparatus for 35 use with a single magneto or for use with two magnetos associated with a single engine and two arrangements according to the invention as applicable to two magnetos are illustrated diagrammatically by way of example in the accompanying drawing, in which

Figure 1 shows one arrangement as applied to 40 two magnetos of an engine in which the magnetos supply alternate sparks,

Figure 2 shows an arrangement as applied to 45 two magnetos of an engine in which the magnetos supply simultaneously sparks,

Figure 3 is a somewhat diagrammatic side elevation of a combined interrupter and electromagnetically controlled switch of the kind employed in the construction shown in Figure 2, and

Figure 4 is a diagrammatic plan of the con-

struction of switch diagrammatically shown in Figure 3.

In the construction diagrammatically shown in Figure 1 the magnetos A and B are each of conventional type including a primary winding A¹, B¹ in parallel with a condenser A², B² and the mechanically operated contact-breaker A³, B³, and a secondary winding A⁴, B⁴ one end of which is connected to earth while its other end is connected to the central electrode of the usual distributor A⁵, B⁵.

The unearthing ends of the primary windings of the two magnetos are adapted to be connected by conductors A⁶, B⁶ and an electromagnetically controlled switch C to opposite ends of the secondary winding D¹ of a transformer D. The primary winding D² of the transformer D is arranged in a primary circuit D³ including a battery E and an interrupter F of the buzzer type operated by the stray field from the transformer D, this circuit being controlled by a manually operated switch G.

Arranged in parallel with the primary winding D² is the operating coil C¹ of the switch C which when energised is arranged to close the switch.

The operation of the apparatus is as follows. When the switch G is closed the coil C¹ and the primary winding D² are energised. The interrupter F thus comes into operation and simultaneously the switch C is closed to connect the two magneto primary windings A¹ and B¹ to the secondary winding D¹ of the transformer D. Since the two magnetos A and B supply alternate sparks the contact-breaker of one magneto is always closed when that of the other opens. The closed contact-breaker thus earths one end of the secondary winding D¹ and thus completes the circuit through this winding and the primary winding of the other magneto. In this way as long as the switch G is kept closed a series of low tension current impulses are delivered to the primary winding of whichever of the two magnetos at any moment has its contact-breaker open. When the engine has been started, the switch G is released, whereupon the switch C opens to break communication between the magnetos and the energising apparatus.

It will be seen that the energising apparatus (constituted by the apparatus enclosed in a dotted line) can be arranged and constructed as a unit which can then be coupled to the battery E and switch G by a pair of conductors and to the magnetos by a further pair of conductors. Further these latter conductors may be the same as the normal earthing conductors leading to the usual ignition switch.

In the alternative construction illustrated in Figure 2 the magnetos A and B are of the same conventional type as shown in Figure 1 but are adapted to supply simultaneous sparks. To this end the conductors A⁶, B⁶ are adapted to be connected through switch apparatus H respectively to opposite ends of the secondary winding J¹ of a transformer J, the centre of this winding being earthed as shown. In this construction, as in the construction shown in Figure 1, the primary winding of the transformer J is arranged in a primary circuit including a battery K and an interrupter K¹ of the buzzer type operated by the stray field from the transformer, the primary circuit being controlled by a manually operated switch L.

In this arrangement the switch H for coupling the secondary winding J¹ to the magnetos A and

B is also arranged to be operated by the stray field from the transformer J. To this end the switch H comprises a spring leaf M anchored at M¹ and carrying at M² an armature of such weight that when drawn into contact with the end of the core of the transformer J it will remain in contact therewith in spite of the intermittent nature of the current caused by the interrupter K¹. In order to assist this the armature M² is as shown connected to the leaf M at a single point so that it can rock to a small degree without materially distorting the leaf and can thus readily bed down on the end of the transformer core. Also carried by the leaf M but insulated therefrom are two contacts M³, M⁴ connected by flexible leads M⁵ respectively to the conductors A⁶ and B⁶ and adapted when the transformer J is energised to engage contacts M⁶, M⁷ connected respectively to opposite ends of the winding J¹.

Also arranged in the circuit of the battery K and arranged to be closed by the switch L is the operating coil of an electromagnetic switch O arranged to bring an electric engine starter into operation.

The operation of the apparatus shown in Figure 2 is as follows. When the switch L is closed the primary winding of the transformer J is energised, the interrupter K¹ comes into operation, the switch H is closed and hence a series of low tension current impulses are transmitted through the conductors A⁶ and B⁶ from the secondary winding J¹ to the primary magneto windings. At the same time the switch O is closed to bring the electric starter into operation and hence cause rotation of the engine crankshaft. Starting of the engine is thus effected whereupon the switch L is opened and the engine continues to operate in the normal way.

In this construction also it will be seen that only two leads are required to the energising apparatus (enclosed in a dotted line) from the battery and switch L and only two leads from this apparatus to the magnetos.

Figures 3 and 4 show still somewhat diagrammatically how the combined transformer J, interrupter K¹ and switch H may be constructed. Thus it may comprise a casing P in which the transformer proper is disposed with the ends J², J³ of the transformer core projecting from opposite ends of this casing. Disposed adjacent to the end J³ of the core is a spring-mounted interrupter armature K² carrying a contact K³ normally making contact with a contact K⁴ on a spring leaf K⁵, the contacts K⁴, K³ thus constituting an interrupter of the buzzer type in the circuit of the primary winding of the transformer.

Disposed adjacent to the end J² of the core is the armature M² supported on the spring leaf M. In this construction however, instead of the contacts M³, M⁴ being directly carried by the leaf M they are carried by separate leaves M⁸, M⁹ arranged to be acted upon by a strip of insulating material M¹⁰ secured to the leaf M. Actually the opposite ends of the winding J¹, shown dotted in the left half of Figure 3, are connected as shown in Figure 2 respectively to two contacts M⁶, M⁷ arranged one behind the other in this figure and arranged to make contact respectively with the contacts M³ and M⁴ as in Figure 2, as previously described.

What I claim as my invention and desire to secure by Letters Patent is:

1. Energising apparatus for supplying low tension current impulses to the primary winding of a high tension magneto of an internal combustion

tion engine, comprising a primary circuit including an interrupter and adapted to be connected to a source of current, and an electromagnetically operated switch for controlling the connection between the energising apparatus and the primary winding of the magneto arranged to close and open automatically as the primary circuit is respectively energised and deenergised.

2. Energising apparatus for supplying low tension current impulses to the primary winding of a high tension magneto of an internal combustion engine, comprising a primary circuit including an interrupter of the buzzer type arranged to be connected to a source of current, an electromagnetically operated switch for controlling the connection between the energising apparatus and the primary winding of the magneto arranged to close and open automatically as the primary circuit is respectively connected to and disconnected from the source of current.

3. Energising apparatus as claimed in claim 2, in which the electromagnetically operated switch is actuated by the stray field from the coil of the interrupter.

4. Energising apparatus as claimed in claim 2, in which the interrupting contacts constituting the buzzer lie at one end of the core of the coil while the contacts of the electromagnetically operated switch lie at the other end thereof.

5. Energising apparatus as claimed in claim 2, in which the primary circuit includes the primary

winding of a transformer, the secondary winding of which is arranged to be connected to the primary winding of the magneto by the electromagnetically operated switch.

5. Energising apparatus as claimed in claim 2, in which the interrupter is operated by the stray field from a transformer the primary winding of which lies in the primary circuit while the secondary winding is arranged to be connected to the primary winding of the magneto by the electromagnetically operated switch.

6. Energising apparatus as claimed in claim 2, in which the electromagnetically operated switch comprises an armature arranged to be drawn into contact with a core when the latter is magnetised electrically and of such weight as to remain in contact therewith as long as the primary circuit is connected to the source of current in spite of the interrupted nature of the current in that circuit.

10 7. Energising apparatus as claimed in claim 2, in which the electromagnetically operated switch comprises an armature arranged to be drawn into contact with a core when the latter is magnetised electrically and of such weight as to remain in contact therewith as long as the primary circuit is connected to the source of current in spite of the interrupted nature of the current in that circuit.

20 8. Energising apparatus as claimed in claim 2, in which an armature is operated by said switch and is carried by a spring leaf whereby the switch contacts are directly or indirectly moved.

25 9. Energising apparatus as claimed in claim 2, in which an armature is operated by said switch and is mounted on a spring leaf so as to be capable of limited rocking movement relatively thereto without materially distorting the leaf so as to facilitate the bedding of the armature on the core.
